SEAMING MECHANISM

Paul H. Lange, Bridgeport, Conn.

Application June 15, 1933, Serial No. 675,898

5 Claims. (Cl. 113—24)

This invention relates to new and useful improvements in seaming mechanism and has particular although not exclusive relation to a seaming mechanism employing a plurality of first operation seaming tools and a plurality of second operation seaming tools.

The invention provides a simple and compact structure of seaming mechanisms and a mechanism which is well balanced whereby vibration and wear are reduced. Also, the invention includes certain details of construction as will later be fully set forth.

While in the accompanying drawings and following description the details of one satisfactory embodiment of the invention are fully set forth it is to be understood that the invention is not limited to the details disclosed but includes all such variations and modifications as fall within the spirit of the invention and the scope of the appended claims.

In the drawings:

Fig. 1 is a bottom plan view of a seaming head constructed according to the invention;

Fig. 2 is a vertical sectional view taken substantially along the plane of the line 2—2 of Fig. 1;

Fig. 3 is a vertical sectional view taken substantially along the plane of the line 3—3 of Fig. 1;

Fig. 4 is a vertical sectional view taken substantially along the plane of the line 4—4 of Fig. 1;

Fig. 5 is a bottom plan view of the seaming cams;

Fig. 6 is a detail side elevational view showing the mounting for a cam roller;

Fig. 7 is a detail sectional view taken substantially along the plane of the line 7—7 of Fig. 2;

Fig. 8 is a top plan view of an eccentric seaming roller mounting spindle employed; and

Fig. 9 is a side view of the pin of Fig. 8, a part being broken away.

Referring in detail to the drawings, the improved seaming mechanism includes a head generally designated 10 and comprising a disc-like portion 11 which at its outer edge carries an upstanding flange 12. A chuck 13 of any or the usual construction is provided to hold the work and such chuck is mounted on a stationary shaft 14 extending through a tubular member or sleeve 15 connected to or integral with the member 11. Any suitable means may be used for rotating the sleeve 15 and the motion of such sleeve will, of course, be imparted to the disc-like portion 11 and the various means carried thereby which means will later be more fully referred to.

Depending from the disc-like portion 11 are spaced lugs or extensions 16 (see Fig. 4) and secured to these lugs or extensions are four cover

guide members 17. Disposed between two of the cover guide members and the disc-like portion 11 are a pair of seaming tool carriers 18 each in the form of a bell crank. Mounting pins 19 pass through the intermediate portions of the carriers or bell cranks 18 and said mounting pins are secured in or to the disc-like portion 11 and the closure 17 as clearly shown in Fig. 4. From this it will be understood that the carriers or bell cranks are adapted for a rocking movement or turning movement on the pivot pins or bolts 19.

At each of its ends each carrier 18 mounts a seaming tool. First operation seaming tools 20 are mounted on the diametrically opposite end portions of the bell cranks while second operation seaming tools 21 are mounted on the other diametrically opposite end portions of the bell cranks. From this it will be understood that the seaming tools are arranged in pairs the tools diametrically opposite each other in each instance constituting a pair. Each seaming tool is mounted for fine adjustments and to accomplish this each tool is mounted on a spindle 22 having an outer end portion 23 and an inner end portion 24 which end portions are eccentric with respect to one another as clearly shown in Figs. 8 and 9. The inner end portion 24 of each spindle is received in an opening in the carrier 18 while the outer end portion of each spindle mounts a seaming tool.

Each spindle is provided with a flange like portion or collar 25 having openings 25A therein for the reception of a pin or spanner wrench or the like whereby the spindle may be slightly rotated to adjust the position of the seaming tool carried by it. Associated with the inner end portion of each of the spindles 22 is a key 26 which extends for substantially the length of the said inner end portion of the spindle. Extending through the carrier transversely with respect to each key is a bolt 27 and each of said bolts includes an inclined edge portion 28 (see Fig. 7). The arrangement is such that on the tightening of the nut 29 of the bolt the inclined surface of that bolt will be drawn against the key 26 with which the bolt is associated and said key will be forced against the inner end portion of that spindle associated with the key.

It will, therefore, be understood that on loosening of a nut 29 the spindle associated with said nut may be adjusted to adjust the position of a seaming tool on said spindle and thereafter on tightening of the nut the key 26 will be jammed against the spindle locking the latter and its seaming tool in adjusted position. The means disclosed is inexpensive and very effective for the purpose intended and since the spindle is engaged over a large area it will not be damaged.

30 in each instance is a carrier on which a cam roller 31 or 32 is mounted, and it will be 30

noted that said carriers extend through cut-away portions 16 of the disc-like portion 11 above referred to. Each carrier 30 is connected with or attached to one of the bell cranks 18 5 as by means of a bolt 33 and there is interposed between the carrier and the bell crank a resilient or yielding member such as a spring 34 so that when the second operation seaming tools pass over the side seam of a can the said tools may 10 yield slightly without transmitting the strain to the cam rollers.

The cam rollers are located above the upper surface of the disc-like portion 11 of the seaming head and within the flange 12 of said head 15 there is arranged a cam member 35 having a tubular portion 35A by which it may be driven. As clearly shown in Fig. 2 the cam member 35 receives the cam rollers 31 and 32 and it is noted that said cam rollers are mounted as on 20 pins 36 extending vertically from the carriers 30. It will be noted that the rollers 31 and 32 are reversed with respect to one another whereby to properly cooperate with the cams of the carrier 35 as will be set forth.

25 Cam member 35 is provided with a track or groove 37 containing cams 38, 39, 40 and 41 of which cams 38 and 39 form one pair while cams 40 and 41 form the other pair. The cam 39 is arranged in vertically spaced relation to the cam 30 38 and the cam 41 bears the same relation to the cam 40 as does the cam 39 to the cam 38. Therefore, as the machine is operated when one cam roller is in engagement with the cam 38 the other cam roller is in engagement with the cam 39. As the rollers ride up on these cams the bell cranks 18 are rocked on their pivots 19 whereby the first operation seaming tools are carried in against the work and the second operation seaming tools are moved outwardly 35 from a neutral position. As is customary in machines of this character the seaming head and the seaming cams are given a relative rotating motion.

40 As the machine progresses the cam rollers move off the cams 38 and 39 so that the seaming tools all occupy neutral positions and next the cam rollers ride onto the cams 40 and 41 whereby the second operation seaming tools are carried in against the work while the first operation tools 45 are swung outwardly from neutral positions. From this it will be understood that as the first operation seaming tools move inwardly to operative position the second operation tools move outwardly and as the first operation seaming tools 50 move outwardly from the work the second operation seaming tools are moved against the work. The cams positively operate the bell cranks in both directions and since each bell crank carries a tool at each of its ends the movement of one 55 tool in one direction is balanced by a movement of the other tool in the opposite direction so that there is no tendency to throw the machine off balance and cause it to wobble or vibrate and rapidly wear.

60 Having thus set forth the nature of my invention, what I claim is:

1. In a seaming mechanism, a seaming tool carrier having an opening therein, a seaming tool spindle, said spindle including inner and outer end portions, a seaming tool on the outer end portion of said spindle, said spindle having its inner and outer end portions eccentric with respect to one another, said spindle having its inner end 70 portion extending into the opening in the carrier,

a key in said opening in the carrier and extending longitudinally of the spindle, and means extending transversely of and in engagement with the key intermediate the ends thereof and operable to force the key against the inner end portion of the spindle to lock the spindle in adjusted position relative to the carrier. 5

2. In a seaming mechanism, a seaming tool carrier having an opening therein, a seaming tool spindle, said spindle including inner and outer end portions, a seaming tool on the outer end portion of said spindle, said spindle having its inner and outer end portions eccentric with respect to one another, said spindle having its inner end portion extending into the opening in the carrier, a key in said opening along one side thereof and extending longitudinally of and engaging the inner end portion of the spindle over a substantial portion of its length, said key having a flat side, a wedge means extending transversely of said key and having a flat side engaging the flat side of the key intermediate the ends thereof, and means to draw said wedge transversely of the key to cause it to force the key against the inner end portion of the spindle to lock the latter in adjusted position in the carrier. 15

3. In a seaming mechanism, a head, a pair of seaming tool carriers each comprising a bell crank, means pivoting said bell cranks substantially midway their lengths to said head at substantially diametrically opposite points on the head, a plurality of seaming tools, means mounting one of said tools on each end portion of each of said bell cranks whereby the tools diametrically opposite each other form pairs, a cam roller directly on the upper side of each of said bell cranks in spaced relation to and independent of its pivot means, and a cam immediately above said bell cranks and having a groove receiving said cam rollers to turn the bell cranks on their pivots. 30 35

4. In a seaming mechanism, a head, a pair of seaming tool carriers each comprising an elongated rigid member, means pivoting said members substantially midway their lengths to the head at substantially diametrically opposite points on the latter, four seaming tools, means mounting one of said tools on each end portion of each of said members whereby the tools diametrically opposite each other form pairs, a cam roller directly on the upper side of and at one end portion of each of said carriers and independent of the pivot means of the latter and cam means immediately above and engaging said rollers to rock the carriers to alternately move the pairs of tools toward and from the work. 45 50 55

5. In a seaming mechanism, a head, a pair of seaming tool carriers each comprising an elongated rigid member, means pivoting said members midway their lengths to the head at substantially diametrically opposite points on the head, a plurality of seaming tools, means mounting one of said tools on each end portion of each of said members whereby the tools diametrically opposite each other form pairs, a cam roller directly on the upper side of and at one end portion of each of said carriers and independent of the pivot means of the latter, cams directly above and engaging said rollers to rock the carriers to alternately move the pairs of tools toward and from the work, and said cams constructed and arranged to operate said members positively in each direction about their pivots. 60 65 70 75
